UNITED STATES PATENT OFFICE.

BENJAMIN D. SANDERS, OF CROSS CREEK DISTRICT, (WELLSBURG P. O.,)
WEST VIRGINIA.

APPARATUS FOR CLEANING AND WARMING GRAIN.

SPECIFICATION forming part of Letters Patent No. 240,769, dated April 26, 1881.

Application filed January 6, 1881. (No model.)

To all whom it may concern:

Be it known that I, BENJAMIN D. SANDERS, of Cross Creek District, (Wellsburg P. O.,) county of Brooke, State of West Virginia, have 5 invented or discovered a new and useful Improvement in Apparatus for Cleaning and Warming Grain; and I do hereby declare the following to be a full, clear, concise, and exact description thereof, reference being had to the 10 accompanying drawings, making a part of this specification, in which—like letters indicating like parts—

Figure 1 is a sectional perspective view of my improved grain cleaning and warming apparatus. Fig. 2 shows a vertical sectional elevation of the same, the section being taken in the plane of the line $x x$ of Fig. 3; and Fig. 3 shows a transverse section in the plane of the line $y y$, Fig. 2.

20 My invention relates to an improved apparatus for cleaning and warming grain preparatory to grinding; and it consists in subjecting the kernels of grain to frictional action by rubbing them over each other, when confined under pressure, by means of an angular-shaped drum arranged to rotate within a polygonal stand pipe or box which holds or contains the grain.

The advantages of cleaning wheat of its fuzzy 30 outer coating, as well as of smut and other foreign matter, as a preparatory step to grinding, is well understood. Various kinds of devices have been used for this purpose, including the ordinary smut-mills, decorticators, and 35 grain-scourers; but in practice all these machines are more or less open to the objection that the work of cleaning is but partially or imperfectly done, or else the grain is subjected to such severe treatment that the husk or bran 40 is broken or abraded and worn away in some places to such extent as to greatly weaken it and cause an undue portion to be comminuted or pulverized in the operation of grinding, and thereby become mixed with the flour, which is 45 well understood to be injurious and very objectionable.

It is also considered desirable to warm or heat the grain preparatory to grinding, not only for the purpose of drying it, but also to 50 toughen the husk or bran, and thereby prevent

its comminution. Various devices have been employed for this purpose, which, so far as I am aware, effect the result by the application of artificial heat, either directly from a fire, or indirectly by heated air or other medium. 55

Such apparatus, as well as that for cleaning, is expensive when so made as to be of practical value, and is scarcely within the means of a large class of millers.

The purpose of my invention is to enable a 60 miller, with the most trifling expense, to clean and warm or heat his grain preparatory to grinding in the best and most efficient manner without subjecting it to the injurious treatment referred to as characteristic of old machines. 65

The apparatus which I employ is constructed as follows:

In the drawings, A represents a rectangular box placed in a vertical position, and there secured in any convenient way to the floor-timbers of the building, or to any other suitable support. This box may be of any desired size in cross-section, and its height is, by preference, six or more feet, depending somewhat 75 upon the character and amount of work to be done.

Within the box is mounted or journaled a rotary drum or stirrer, B, which is, by preference, made rectangular in cross-section, and is 80 mounted on a rotary shaft, B', in the central or axial line of the box. The shaft may be supported by a step-bearing, c, secured on the bottom of the box, as in Fig. 2, or below the box, on an independent supporting-timber, C, 85 as in Fig. 1. A journal-box, c', receives the upper end of the shaft, and rotary motion or driving-power may be imparted by band-wheel C', or in any other desired way.

I have shown the drum B made hollow, and 90 it is keyed to the shaft by wedges b^2 at the closed ends b' , and also at intermediate points, if desired. The drum may be made solid, however, if preferred. The size of the drum is, of course, considerably less than the box, and it 95 may be varied more or less, as desired, though sufficient space should be left between the angles of the drum and the inner side walls of the box, when in the position shown in full lines, Fig. 3, to prevent breaking or cracking 100

of the grain—say three-eighths of an inch, more or less.

As the drum is rotated within the box the body of grain, which fills to a greater or less height the space between the two, will be constantly turned and shifted by the ever-changing form of the space which it occupies. This changing form is due to the different positions which the drum assumes with relation to the sides and angles of the box, and it is partially illustrated by the diagrams in dotted lines, Fig. 3. This shifting or changing form results in rubbing the kernels of wheat over, upon, and against each other, and by such frictional rubbing of the kernels the fuzzy coating is worn off and the bran coating polished and toughened in the best possible manner. This result is due, in part at least, however, to the fact that the grain is subjected to pressure, especially toward the bottom of the box, by the body of grain above, and such weight or pressure not only assists in cleaning, as stated, by increasing the friction of the rubbing-surfaces, but the grain is gently and uniformly warmed, and is thereby brought into the best possible condition for grinding. The degree of heat or warmth obtained will depend in part upon the weight of the column of grain, the rate of rotation of the drum, and the length of time the grain is subjected to such treatment.

In order to secure the best results, I prefer to make the box six feet or more in height, so as to obtain a considerable column and weight of grain, also to give the drum a speed or rate of from sixty to one hundred and twenty revolutions per minute, more or less, not so great, however, as to cause violent beating of the grain against the sides of the box, and the length of time during which the grain is retained, together with the degree of pressure, may be regulated as follows: A discharge-spout, D, is made in the bottom of the box, in any convenient way, as in Fig. 1, or in one side close to the bottom, as in Fig. 2. Within this discharge-spout is a hinged gate, d, to which is secured, on the outside of the spout, a lever, e, and sliding weight E. This lever is so arranged that the effective weight of E tends to keep the gate closed as against pressure from within the box. When, however, such pressure exceeds a certain amount, the gate is partially opened and grain flows out at a rate corresponding to the inflow through a suitable spout, F, at the top of the box. Any suitable means may be employed to regulate this inflow of grain through spout F.

By moving weight E upon the lever the degree of pressure within the box can be varied and the grain be warmed or heated by friction, during the operation of cleaning, to any degree within the range which it is prudent to heat grain preliminary to grinding.

Any suitable apparatus may be employed for separating the dirt and dust from the wheat as or after it leaves the spout D.

When the shaft B' passes through the slop-

ing bottom of the box, as in Fig. 1, the opening may be made to fit the shaft closely, or be packed in any convenient way to prevent escape of grain.

The drum B may be made triangular or of other angular form in cross-section, and good results secured thereby. Also, the box A may have six, eight, or other desired number of sides; but I prefer to make both box and drum square in cross-section, in order better to secure a thorough shifting and frictional rubbing of the kernels of grain over and against each other throughout the entire bulk.

The box and drum may be made either of metal or wood, though if made of wood it should be lined or faced with metal sheets, to prevent rapid wearing away.

An important advantage which I secure by this construction of apparatus over cylindrical cases with interior rotary stirrers, such as screws, arms, and pins or beaters, heretofore known, is a much more uniform and thorough shifting and rubbing of the grain throughout its entire bulk, thereby securing more uniform cleaning and better treatment. This is due to the constantly-changing form of the space between the box and drum, and to the fact that the whole body of grain is carried around, more or less, with the drum from angle to angle of the box, and as the corners of the drum pass the sides and corners of the box there is also a vertical or lifting-and-falling movement of the grain, thereby more effectually shifting and rubbing the kernels than can be done either by a screw-shaped stirrer or by rotary arms or beaters. With a screw-shaped stirrer the grain is given a sliding motion through the apparatus, with rotary arms, beaters, or pins projecting into the space occupied by grain, the rubbing action of the grain is not thorough or uniform, owing, in part, to the fact that the weight of grain tends to prevent free motion, and those kernels lying nearest to the arms or beaters are shifted most.

Grain-cleaning devices are also known having cone-shaped case and drum, with corrugations formed on the adjacent faces, like the roughened grinding-surfaces of a grain or coffee mill; but in such apparatus the grain-containing space is of substantially one constant form, and the roughened or corrugated surfaces are designed especially to break the husk of the grain and wear it away, and in this respect such surfaces are designed and adapted to accomplish the very thing which it is the purpose of my invention to avoid—namely, abrading and wearing away the bran. Such cone-shaped case and drum, with abrading or reducing surfaces, do not embody my invention, and I make no claim to such construction.

I claim herein as my invention—

1. In a machine for cleaning and warming grain, a box or case, A, square in cross-section, having an inlet, F, at the top and an outlet, D, at the bottom, the capacity of the latter being adjustable with reference to the supply,

as described, in combination with rotary drum B, square in cross-section, the distance between diagonal corners of the drum being less than the width of a side of the box, substantially as and for the purposes set forth.

2. The combination of a box, A, of polygonal form in cross-section, having an inlet, F, and outlet D, a drum, B, of polygonal form in cross-section, and arranged to rotate within the box, both box and drum having plain side faces, be-

tween which the grain is contained, with gate d and means for closing the gate against a given pressure within the box, substantially as set forth.

In testimony whereof I have hereunto set 15
my hand.

BENJAMIN D. SANDERS.
